REFRIGERATING APPARATUS

Theodore W. Koerner, Detroit, Mich., assignor,
by mesne assignments, to Nash-Kelvinator
Corporation, Detroit, Mich., a corporation of
Maryland.

Application July 2, 1935, Serial No. 29,536

1 Claim. (Cl. 62—126)

My invention pertains to refrigerating apparatus of the expansion type and more particularly to an improved refrigerant evaporator and method of making the same.

5 It is an object of my invention to provide a refrigerant evaporator construction which is of smooth regular conformation having spaced inner and outer walls the edges of one of the walls being turned to provide a smooth rolled periphery and abutting the edges of the other wall to which it is welded to define a substantially smooth flat surface whereby the evaporator may be covered uniformly with a protective coating of a substance such as a vitreous enamel.

10 It is also an object of my invention to provide a refrigerant evaporator which may be readily constructed from flat sheet metal blanks united to provide inner and outer walls having their edges turned together to define a smooth flat surface and a smooth rolled upper periphery.

15 It is a further object of my invention to provide an improved refrigerant evaporator and method of making the same of spaced inner and outer walls of sheet metal which comprises folding the edge of either the inner or the outer sheet to provide a smooth rolled periphery, terminating the inturned edge thereof abutting the edge of the other sheet and welding the abutting edges together to define a substantially flat smooth surface.

20 The invention itself, however, both as to its organization and its method of operation, together with additional objects and advantages thereof, will best be understood from the following description of a specific embodiment, when read in conjunction with the accompanying drawing, in which:

25 Fig. 1 is a side elevational view partly broken away and sectioned showing a refrigerant evaporator constructed in accordance with my invention;

30 Fig. 2 is a cross-sectional view on line II—II thereof;

35 Figs. 3 and 4 are detail sectional views on lines III—III and IV—IV thereof;

40 Fig. 5 is an elevational view showing a blank sheet of metal which may be folded to provide side walls of the evaporator; and

45 Fig. 6 is a side elevational view illustrating a stage in the construction of an evaporator after a corrugated sheet has been united with the blank sheet, the edges of which have been folded over before the united structure has been bent into a U shaped cross-sectional form.

5 Referring more specifically to Figs. 1 and 2 of the drawing I have shown a cooling unit 1 constructed in accordance with my invention for absorbing heat by the vaporization of a volatile refrigerant therein. Such an evaporator consists of an outer side wall 3, the outer edges of which are bent upwardly to provide a U shaped cross sectional conformation, enclosing and spaced from an inner wall 5 which is likewise of a U shaped conformation.

10 In order that the walls 3 and 5 may be rigidly secured in spaced relation to provide space for the vaporization of a volatile liquid refrigerant therebetween, a plurality of parallel spaced corrugations 7 are provided in the metal sheet 3 forming the outer walls of the evaporator. The portions 9 between the corrugations 7, in the outer wall directly engage the inner wall 5 to which they are spot welded at intervals although a hermetically sealed engagement therebetween 15 is neither necessary nor desirable. As shown, the refrigerant receiving corrugations 7 in the outer wall 3 extend vertically down the sides of the evaporator and pass under the bottom thereof where they connect a large feeder corrugation 11 20 which extends longitudinally along the center of the bottom wall for supplying liquid refrigerant to the smaller corrugations 7 branching therefrom. The inner wall 5 of the evaporator is provided with large horizontally disposed corrugations 13 near the upper edges thereof which comprise refrigerant manifolds for drawing the refrigerant vapor from the upper ends of the vertical corrugations 7 along the sides. For this purpose a tubular vent 15 extends transversely 25 across the upper portion of the evaporator having its opposite ends operatively connected to the refrigerant manifolds 13 in the inner walls of the evaporator, as shown in Figs. 2 and 3. The ends of the vent 15 are hermetically sealed into 30 suitable apertures provided in flattened portions 14 in the manifolds 13 in any suitable manner, as by welding for example. Smaller horizontal corrugations 16 at a lower level in the inner walls 5 serve to support shelves or partition members in 35 the evaporator and also interconnect the vertical corrugations 7 to circulate the refrigerant. The uppermost edges of the inner and outer walls of the evaporator are united by folding over the edges of either the inner or the outer sheet to 40 form a smooth rolled periphery 11 around the upper edges of the evaporator. The edges of the lower walls and the vertically extending edges are similarly united to provide smooth rolled peripheries 11. The folded edges abut the extended 45

50 55

edges of the other sheet to define a substantially flat surface therewith. As shown in the present embodiment the edges of the inner wall 5 are folded outwardly and extend back along the inner 5 surface of the wall 5 to abut the edges of the outer wall 3. The abutting edges defining a substantially flat smooth surface are conveniently seam welded together close to the abutting edges as by means of seam welding rolls, or in any 10 suitable manner, as will be readily understood by those skilled in the art. The vent tube 15 interconnecting the manifolds 13 is provided with an aperture extending through the upper wall thereof for connection with the suction line 18 of a 15 refrigerating system. The aperture comprises a down pressed flange portion 21 for supporting a suitable connection fitting 23 which may be threadably engaged therein for operatively connecting the suction line conduit 19 thereto. The 20 volatile liquid refrigerant is supplied to the evaporator 1 through an inlet fitting 25 located centrally between the edges of the lower walls of the evaporator in the open end of the large feeder corrugation 11 as shown in Figs. 1 and 4. An 25 annular ring 27 is secured between oppositely diverging portions of the bottom walls 3 and 5 of the evaporator where it may be secured in any suitable manner, as by welding or soldering. An aperture passing through the ring 27 is threaded 30 to receive the inlet fitting 25 which is threaded therein and serves to operatively connect a refrigerant line 29 extending from the refrigerant condenser or other source of refrigerant to the evaporator. In constructing my refrigerant evaporator 35 a first blank sheet 31 is provided having restricted corners 33, as shown in Fig. 5, and the outwardly projecting edges of the sheet are folded back along the adjacent dotted lines 35. When the edges of the blank are turned back to a position corresponding to the innermost dotted line 37, the 40 smooth rolled edges 17 are provided around the periphery of the sheet and the inturned edges project inwardly substantially along the innermost dotted line 37 being flattened against the sheet. A second sheet 39 comprising the outer 45 wall 3 of the evaporator, is placed upon the blank sheet with its outwardly projecting edges abutting the inturned edges of the blank thus defining a substantially smooth flat surface therewith. The abutting edges are then seam welded together 50 as by passing them between seam welding rollers 41, as shown in Fig. 3, or in any suitable manner as will be readily understood by those skilled in the art. As will be understood the two sheets 31 and 39 are provided with suitable refrigerant circulating corrugations such as 7, 13, and 16 before 55 they are united.

The mutually engaging surfaces between the corrugations 7 of the outer wall are disposed in intimate engaged relation against the surfaces of the inner wall and the engaging portions are spot welded at intervals to provide a rigidly united structure, as shown in Fig. 6. After the inlet

connection 25 has been secured between the spaced edges of the sheets, as previously set forth, the fabricated structure is then distorted into the substantially U shaped cross sectional conformation, as shown in Fig. 2. The refrigerant vent tube 15 is then inserted between the refrigerant manifolds 13 which have apertures into which it is hermetically sealed as by welding or soldering as previously set forth. It will be understood that the method of construction is similar whether 10 the edges of the inner wall of the evaporator are turned outwardly to make the smooth rolled periphery 17 integral with the inner wall as shown, or the edges of the outer wall are turned inwardly to make roll 17 integral with the outer 15 wall. By providing rounded corners on the blank sheet there are no welded joints at the corners when it is bent to form the finished evaporator.

In my construction the disadvantages of previous evaporators presenting sharp corners and 20 edges is entirely eliminated, and the completed structure may be provided with a uniform coating of enamel such as porcelain which will be of uniform thickness overall to protect it from corrosion and present a sanitary pleasing appearance, and it is ready for mounting within a compartment to be refrigerated thereby. 25

It will be seen that I have provided an improved evaporator and method of constructing the same whereby the sharp edges of the blank sheets are 30 conveniently turned and welded together in abutting relation and only smooth flat and rolled surfaces are exposed on which a vitreous enamel may be coated uniformly throughout.

Aside from the specific embodiment of the invention herein shown and described, it will be understood that numerous details of the construction may be altered or omitted without departing from the spirit and scope of the invention as disclosed and claimed, and that I do not desire to 40 limit the invention to the exact constructions herein set forth. 35

I claim as my invention:

A sheet metal refrigerant evaporating element comprising sheet metal material formed to provide inner and outer walls spaced apart for the passage of refrigerant and an inlet opening, one of said walls including material integrally united therewith and having a reversely bent portion forming a rolled bead extending continuously, 45 except for said inlet opening, around the periphery of the said one wall including the four corners thereof, the extreme edge of said reversely bent portion being in uniformly continuous abutting engagement with the peripheral edge of the material forming the other wall and said extreme and peripheral edges being located at sufficient distance from said rolled bead to permit seam welding between the material forming one wall and the return bend of said material and also to 50 permit seam welding between the two walls with the same operation of seam welding. 55
